United States Patent Office

Des. 177,759
Patented May 22, 1956

177,759

DESK UNIT

Eugene W. Pike, Jr., Carteret, N. J., assignor to Helen P. Pike, Carteret, N. J.

Application November 18, 1955, Serial No. 38,953

Term of patent 7 years

(Cl. D74—1)

Fig. 1 is a front perspective view of a desk unit showing my new design; and

Fig. 2 is a rear elevational view thereof.

The broken line illustration of the pen shown on the drawing is for illustrative purposes only.

I claim:

The ornamental design for a desk unit, as shown and described.
